UNITED STATES PATENT OFFICE.

EDWIN J. HART, OF PHILADELPHIA, PENNSYLVANIA.

UNDERFEED STOKER.

1,240,969.

Specification of Letters Patent. Patented Sept. 25, 1917.

Application filed November 23, 1915, Serial No. 62,944. Renewed November 23, 1916. Serial No. 133,096.

To all whom it may concern:

Be it known that I, EDWIN J. HART, a citizen of the United States, residing at Philadelphia, in the county of Philadelphia and 5 State of Pennsylvania, have invented certain new and useful Improvements in Underfeed Stokers, of which the following is a specification.

My invention relates to improvements in 10 underfeed stokers, the object of the invention being to provide a stoker of the character stated which is adapted to burn mechanically various grades of bituminous coal smokelessly and efficiently, and which can be 15 manufactured and sold at a reasonably small price, the up-keep of which will be reduced to a minimum and I preferably utilize the stoker in connection with a blower fan, although it may be used without 20 one if desired.

A further object is to provide a retort with a hollow partition constituting an air chamber and dividing the retort into two compartments which permits the supplying 25 of coal in small quantities over a large area and reduces localized combustion to a minimum. It also prevents the formation of large troublesome clinkers which are common with stokers in general use.

30 A further object is to provide an improved construction of the character stated which may be used under natural draft in the event of a mishap to the equipment, and which embodies in its construction many 35 novel details which coöperate in the performance of improved functions.

With these and other objects in view, the invention consists in certain novel features of construction and combinations and arrangements of parts as will be more fully 40 hereinafter described and pointed out in the claims.

In the accompanying drawings:

Figure 1 is a plan view.

45 Fig. 2 is a view in longitudinal section on the line 2—2 of Fig. 1.

Fig. 3 is a view in transverse section on the line 3—3 of Fig. 1.

50 Fig. 4 is a view in transverse section on the line 4—4 of Fig. 1.

Fig. 5 is a fragmentary view in end elevation showing a portion of the structure on an enlarged scale.

55 Fig. 6 is a view in longitudinal section through one of the set screws 48.

Fig. 7 is a transverse sectional view through the tension plates 46.

Fig. 8 is a fragmentary section on an enlarged scale taken longitudinally through one of the grate bars adjacent the retort. 60

My improved stoker is provided with a central longitudinal retort 1 divided by a central longitudinal hollow partition 2 constituting an air chamber with perforations 2^a in its side walls, so as to direct the air 65 into the fuel.

The retort 1 is located above an air box 3 which communicates with air spaces 4 by means of openings 5. The air spaces 4 are formed between the sides of the air box, and 70 longitudinal plates or partitions 6, the latter having wind gates 7 controlling openings 8 therein, and said wind gates operated by rods 9 to regulate the passage of air from the air box into air chambers 10 below the 75 grate bars 11.

Suitable gates 12 normally close openings in partition plates 13 which extend downwardly from the grate pedestals 14 and enclose the air chamber 10, and into this chamber 10 fine particles of unconsumed fuel are adapted to fall and may be removed from time to time through the doors 19.

The grate bars 11 direct the ash onto dump grates 15 which are operated by 85 rocker shafts 16, and the ash may be removed from the ash pits 17 through doors 18.

The grate bars 11 are so arranged that each alternate grate bar is caused to move 90 by a rocker shaft, and as there are two inclined sets of grate bars, I provide two rocker shafts 20.

Each alternate grate bar is provided with lugs 21 which receive the web 22 of the 95 rocker shaft, while the remaining grate bars have such lugs omitted so that they are not moved by the movement of the rocker shafts.

The grate bars are of the two part type in which the lower member 23 constitutes an 100 air chamber, and the upper member 24 which supports the fuel is provided with a stepped surface 25 having air ports 26 in the sides thereof, so that the air is directed horizontally and in a great many fine jets to entirely consume the fuel.

Each lower grate member 23 is provided with a partition 23^a which divides the air chamber, provided by the member 23, into two compartments 23^b and 23^c (see Fig. 8). 110

The compartments 23^b are directly above the air spaces 4, and the compartments 23^c are directly above the air chambers 10, the partitions 23^a being so positioned above the partitions 6 and rocker shafts 20 that any air passing upwardly through the spaces 4 will pass directly into the compartments 23^b, while the compartments 23^c will receive air directly from the air chambers 10.

16 Air outlet passages 23^d extend outwardly from the compartments 23^b into the chute 30. By this construction, including the partitions 23^a as above described, the air is evenly distributed throughout the entire 15 length of the grate bars, so that each of the air ports 26 as well as the passages 23^d receive a proper amount of air because the air enters the lower portions of the grates through a number of independent sources, 20 namely, the air spaces 4 and the chambers 10.

The air is admitted to the box 3 through a duct 27 communicating preferably with some form of blower (not shown), and 28 is 25 a damper operated by a rod 29 to control the flow of air into the air box.

The retort 1 communicates with an inlet chute 30 into which a hopper 31 discharges the fuel. 32 is a pusher which is connected 30 to a cross head 33 on a piston rod 34, and operates to give the fuel its initial movement along the chute 30. The rod 34 is operated by a piston 35 in a cylinder 36, and steam or other fluid may be utilized as a medium for reciprocating the piston.

The pusher 32 is secured to and reciprocates a pair of rods 37 located at opposite sides of the air partition 2 in retort 1, and boosters 38 are secured to the rods and cause 40 the fuel to move longitudinally of the retort as is well understood.

The rocker shafts 20 above referred to are provided on their outer ends with rocker arms 39, the latter having spherical ends 40 which move in grooves 41 in pivoted plates 42 secured to the cross head 33. These pivoted plates 42 are adjusted by set screws 43 to vary the angular disposition of the slots 41, and it will be understood that the 50 longitudinal movement of the cross head imparts a rocking movement to the rocker shafts 20 by reason of the engagement of arms 39 with slots 41.

The several rocker shafts 20 and 16 are 55 mounted in suitable bearing bars 44, and doors 45 are provided above the grates to permit of hand stoking in the event of accident to the automatic stoker, also in the event of using a natural draft, the doors 18 60 and 19 will be opened but in most cases I prefer a force draft.

To hold the several grate bars in their proper position and to permit a proper assemblage, I utilize suitable tension plates 46 65 at one end of each series of grate bars to

hold the grate bars against lateral movement as shown clearly in the plan view Fig. 1.

The operation is as follows:

Coal is fed mechanically or otherwise into 70 the hopper 31 and is fed forward in the chute 30 by the reciprocation of the pusher 32, advancing the coal in the retort, the boosters 38 assisting in this operation.

The rocker shafts 20 are continuously 75 rocked, and the burning fuel is caused to move along the grate bars until it is consumed, when it falls onto the dump grates 15 and from time to time is dropped into the ash pit 17 below through the medium of any 80 suitable mechanism controlling the shafts 16.

Air enters through duct 27 into air box 3, and is directed through the hollow partition 2 into the fuel at both sides thereof, and also flows through the several ports and chambers above referred to, and supplies the 85 necessary air for a good combustion.

As it is the purpose of my improved stoker to consume the fuel with as little smoke as possible, the arrangement of air supply ports 90 is important because it distributes the air throughout the fuel and provides the necessary oxygen to consume the coal.

All the parts are so arranged as to permit 95 of an adjustment so as to suit the particular fuel consumed, and the parts are so constructed and assembled that they can be readily removed and replaced when it is necessary.

Various slight changes might be made in 100 the general form and arrangement of parts described without departing from my invention, and hence I do not limit myself to the precise details set forth, but consider myself at liberty to make such changes and alterations as fairly fall within the spirit and scope of the appended claims.

Having thus described my invention, what 105 I claim as new and desire to secure by Letters Patent is:

1. In a stoker of the character described, the combination of a longitudinally extending chute, means providing an air supply chamber below the chute, a hollow partition extending longitudinally between the walls 115 of said chute and communicating with said chamber, fuel conveying means located between the walls of the chute and the opposite sides of the partition, said partition having air outlets leading into the fuel as it 120 is conveyed in the chute, substantially as described.

2. In a stoker of the character described, the combination with a retort, and an air supply chamber below the retort, of a hollow partition constituting an air chamber extending throughout the center of the retort having air outlets in its sides and having open communication throughout its length with the air chamber below, and 130

reciprocating boosters in the retort at opposite sides of the partition, substantially as described.

3. In a stoker of the character described, the combination with a retort, and an air supply chamber below the retort, of a hollow partition constituting an air chamber extending throughout the center of the retort having air outlets in its sides and having open communication throughout its length with the air chamber below; a chute communicating with one end of the retort, a hopper communicating with the chute, and a reciprocating pusher below the hopper forcing the fuel in the chute into the retort at opposite sides of the partition, substantially as described.

4. In a stoker of the character described, the combination with a retort, and an air supply chamber below the retort, of a hollow partition constituting an air chamber extending throughout the center of the retort having air outlets in its sides and having open communication throughout its length with the air chamber below, reciprocating boosters in the retort at opposite sides of the partition, a chute communicating with one end of the retort, a hopper communicating with the chute, and a reciprocating pusher below the hopper forcing the fuel in the chute into the retort at opposite sides of the partition, substantially as described.

5. In a stoker of the character described, the combination with a retort, and an air supply chamber below the retort, of a hollow partition constituting an air chamber extending throughout the center of the retort having air outlets in its sides and having open communication throughout its length with the air chamber below, inclined grate bars having their highest ends located at the sides of the retort, means for forcing fuel longitudinally of the retort and over the sides of the retort onto the grate bars, means for shaking the grate bars, and a single motor simultaneously operating both of said last mentioned means, substantially as described.

6. In a stoker of the character described, the combination with a retort, and inclined grate bars at opposite sides thereof, of a hollow partition constituting an air chamber extending throughout the center of the retort and having air outlet perforations in the sides thereof, an air box below the retort having open communication with the partition throughout the length of the latter, boosters in the retort at opposite sides of the partition, rocker shafts adapted to move the grate bars, and means for simultaneously reciprocating the boosters and oscillating the rocker shafts, substantially as described.

7. In a stoker of the character described, the combination with a retort, and inclined

grate bars at opposite sides thereof, of a hollow partition constituting an air chamber extending throughout the center of the retort and having air outlet perforations in the sides thereof, an air box below the retort having open communication with the partition throughout the length of the latter, boosters in the retort at opposite sides of the partition, rocker shafts adapted to move the grate bars, a cylinder, a piston in the cylinder, a rod connected to the piston and operatively connected to the pushers, and means operated by the movement of the piston to oscillate the rocker arms, substantially as described.

8. In a stoker of the character described, the combination with a retort and inclined grates at opposite sides thereof, of a hollow partition constituting an air chamber extending throughout the center of the retort, and having air outlet perforations therein, an air box below the retort communicating with the partition, walls spaced from the air box and having wind gates therein, and said air box having openings communicating with the space between the said walls and the box and directing the air into the grates, substantially as described.

9. In a stoker of the character described, the combination with a retort and inclined grates at opposite sides thereof, of a hollow partition constituting an air chamber extending throughout the center of the retort, and having air outlet perforations therein, reciprocating boosters in the retort at opposite sides of the partition, an air box below the retort communicating with the partition, walls spaced from the air box and having wind gates therein, and said air box having openings communicating with the space between the said walls and the box and directing the air into the grates, substantially as described.

10. In an underfeed stoker, the combination with a longitudinal retort, and inclined grates at opposite sides thereof, of a hollow partition extending longitudinally of the retort and having air outlets in its walls, and an air box below the retort directing air into the partition and having passages at the sides of the box for directing air through the grate bars at opposite sides of the retort, substantially as described.

11. In an underfeed stoker, the combination with a retort and inclined grate bars at opposite sides of the retort, rocker shafts constructed to move certain of the grate bars, a chute communicating with the retort, a hopper communicating with the chute, a pusher in the chute constructed to move the fuel into the retort, a cross head operating the pusher, plates adjustably mounted on the cross head and having slots therein, arms on the rocker shafts located in the slots, and means for adjusting the plates

to vary the angular disposition of the slots, whereby the rocking movement of the rocker shafts is controlled, substantially as described.

- 5 12. In an underfeed stoker, the combination with a retort and inclined grate bars at opposite sides of the retort, rocker shafts constructed to move certain of the grate bars, a chute communicating with the retort, 10 a hopper communicating with the chute, a pusher in the chute constructed to move the fuel into the retort, a cross head operating the pusher, plates adjustably mounted on the cross head and having slots therein, 15 arms on the rocker shafts located in the slots, means for adjusting the plates to vary the angular disposition of the slots, whereby the rocking movement of the rocker shafts is controlled, a fluid cylinder, a piston in 20 the cylinder, and a rod connecting the piston with the cross head, substantially as described.

13. In an underfeed stoker, the combination with a retort, of inclined grate bars at 25 opposite sides of the retort, supporting means for the grate bars, each of said grate bars including an elongated air chamber on their under face, and an upper face of stepped formation, each of said grate bars 30 also having a partition separating its air chamber into two compartments, and means below the grate bars providing two air chambers, one of said latter air chambers being directly below similar compartments 35 of the grate bars while the other of said air chambers is directly below the other compartments of said grate bars, each of said grate bars having ducts leading from one of said compartments to direct the air substantially horizontally, said grate bars each 40 having passages leading from the other compartment into the retort, substantially as described.

14. In an underfeed stoker, the combination with a retort, of inclined grate bars at 45 opposite sides of the retort, each of said grate bars being made in two elongated sections, one of said sections having its upper surface arranged in stepped formation and 50 provided with a series of openings for directing air horizontally, the other of said sections forming a support for the first-mentioned sections and providing an elongated air chamber, partitions in said second

sections dividing the air chamber into two 55 compartments, means for supporting the second grate sections and including a partition in substantial alinement with the partitions of said grate sections and forming two air spaces, one for directing air into 60 similar compartments of each grate bar section, the other of said latter air chambers being located to direct air into the other compartments, and passages leading from the latter compartments in each grate bar 65 and opening into the retort, substantially as described.

15. In an underfeed stoker, the combination with a retort, of inclined grate bars, each of said grate bars made in two sections, 70 one of said sections having its upper surface arranged in stepped formation and provided with a series of openings for directing air horizontally, the other of said sections being of greater length than the first-mentioned sections and providing an elongated air chamber under the first of said sections, a partition in each of said longer sections forming two compartments, said partition being located adjacent the upper ends 75 of said longer sections, means forming a support for the longer sections, and a member forming a partition and providing two air chambers, said partition being substantially in alinement with the partition in said 80 grate sections, and passages leading from the uppermost compartments into the retort, substantially as described.

16. In an underfeed stoker, the combination with a retort, and grate bars at opposite sides thereof, of rocker shafts, arms on the rocker shafts constructed to shake the grate bars, a reciprocating member, plates pivotally supported on the reciprocating member and having slots therein receiving the ends of said arms, and means for adjusting the plates to vary the angular disposition of the slots, whereby the movement of the rocker shafts is varied, substantially as described.

In testimony whereof I have signed my name to this specification in the presence of two subscribing witnesses.

EDWIN J. HART.
